FIG. 3.

FIG. 4.

UNITED STATES PATENT OFFICE

SIMON D. COHEN, OF SAN FRANCISCO, CALIFORNIA

KNITTING MACHINE

Application filed March 13, 1928. Serial No. 261,266.

My invention relates to knitting machines and particularly to those machines usually classified as of the cylinder spring needle type. Especially is my invention concerned with the particular arrangement and composition of the feed devices for applying the thread or yarn to the knitting needles. An object of the invention is to provide a machine which is capable of knitting material which is substantially non-extensible or stretchable.

Another object of my invention is to provide a knitting machine on which substantially non-stretchable material can be produced and in which is used a large number of parts of a standard knitting machine.

The foregoing and other objects are attained in the embodiment of the invention shown in the drawings in which

20 Fig. 1 is a view of a knitting machine arranged according to my invention showing the needle cylinder in plan.

Fig. 2 is a vertical cross section diametrical-
ly thru a knitting machine in accordance with
25 Fig. 1, the plane of section being indicated by
line 2—2 of Fig. 1.

Fig. 3 is an enlarged detail, somewhat dia-
grammatic of the cut presser utilized with
my machine.

30 Fig. 4 is a diagrammatic plan disclosing
one group of feed devices in accordance with
my invention.

Fig. 5 shows one of the needle leads.
In its preferred form, the knitting machine
35 of my invention preferably comprises a feed
device having means for introducing a back-
ing thread into the material and adapted to
knit stitches and cast them off the needles, in
conjunction with a subsequent feed device
40 adapted to introduce an additional thread
into the needles and to cast off only pre-
determined ones of the stitches formed.

While the knitting machine of my inven-
tion is adaptable to a plurality of uses and
45 can be incorporated with various types of
knitting machines as will be clear to those
skilled in the art, I have chosen for illus-
tration and description herein a cylinder
spring needle knitting machine largely of the
50 standard kind.

Such machines usually comprise a table 6
suitably mounted above the floor and pro-
vided with a support for an outside circle
7. The hub 8 of a needle cylinder is provided
with a drive gear 9 meshing with a pinion
11 coaxial with and usually joined by a shaft
55 to a pinion 12. The latter is in mesh with a
gear 13 for driving the take up shaft 14. Both
of the pinions 11 and 12 are rotated by a
bevel gear 15 extending below the table 6 and
meshing with a bevel pinion 16 mounted on
60 the drive shaft 17. Ordinarily tight and
loose pulleys 18 and 19 are provided on the
drive shaft to receive a drive belt 21 from a
source of power. Actuation of the drive
65 shaft 17 rotates the take up shaft 14 and re-
volves the needle cylinder 24 thru the medium
of the described gear trains.

The needle cylinder may comprise an inte-
gral casting with the hub 8 and around its
periphery is provided with a recessed chan-
nel for the reception of needle leads 26 ar-
ranged with their bodies radially of the cyl-
inder and disposed in immediate juxtaposi-
70 tion around the perimeter thereof. To main-
tain the leads 26 in position, removable
clamps 27 are secured to the rim of the cyl-
inder 24 by studs 28. Each of the leads 26
75 preferably includes in the usual manner one
or more spring needles 29 having their bases
set into the lead and having their upper ends
looped over to provide depending beards 31
80 which can be depressed into suitable re-
cesses 32 formed in the needle shanks.

The outside circle 7, which is fixed on the
table 6, is channelled and apertured at in-
85 tervals to receive holding bolts 34 for ad-
justably retaining in position the elongated
links 36. Each of these links is provided
with a longitudinal aperture 37 into which
90 fits a stud 38 projecting from the lower end
of a sinker stand 39. There are a number of
these sinker stands provided for the various
burs and wheels which are comprised in the
feed.

95 Each of the sinker stands preferably com-
prises a generally vertical column 41 to the
upper end of which is affixed a horizontal
journal 42. A shaft 43 is resiliently slidable
100 in the journal 42 and carries at its inner end

one of the various burs or wheels. One or more of the sinker stands 39 can be provided with extensions 44 to receive the adjustable mountings 46 for a revoluble cloth wheel 47 or a relatively stationary cloth cam 48.

5 Concentric with the cylinder 24 and the outer ring 33 is a relatively stationary inner ring 51 usually supported on a sleeve 52 surrounding the drive shaft 14 and supported by a spider 53 merging with the table 6. The inner ring 51 carries on its periphery one or more clamps 54 which are adjustable in all directions and carry mountings 56 for the various burs and wheels situated on the 15 interior of the needle cylinder 24.

In accordance with my invention, I preferably arrange the sinker stands 41 and the various burs and wheels which they carry in a particular order. This order is subject to 20 some variation depending upon the type of material to be manufactured and one illustrative set-up is disclosed in Fig. 1. The various burs and wheels are described in the order they are approached by the needles 25 which revolve counterclockwise when viewed in Fig. 1. Thus, the bur first encountered by the needles is a clearing bur 58 mounted on its respective sinker stand 41 and arranged to insure that the material being knitted is 30 carried from the tops of the needles down below the beards and lies substantially at the bases thereof. This action is initiated by the cloth wheel 47.

Leaving the clearing bur, the needles encounter a sinker bur 59 suitably mounted on a sinker stand 41 and arranged to take yarn or thread thru the eyelet 60 and pass it between the bases and the beards of the needles and up into the heads 61 thereof. The needles are thus charged with a thread extending thru their successive heads and subsequently pass a lander bur 62 mounted on a clamp 54 on the inner circle 51. The lander bur is set to raise the old stitches reposing 45 adjacent the bases of the needles up along the shanks of the needles and over and above the beards thereon to loop with the thread or yarn extending thru the successive heads.

In accordance with my invention, I provide means for selecting certain of the needles to retain the old stitches in the needle heads in conjunction with the thread or yarn introduced by the preceding sinker bur and also for selecting or predetermining others of 55 said needles from which the old stitches are lifted as in the usual process of knitting. This is accomplished by providing a cut presser 63, shown enlarged in Fig. 3, which is preferably mounted on a sinker stand 41. 60 The presser 63 is formed with a serrated edge of any desired pattern and the one disclosed in the figure is simply an example thereof. The undulatory edge of the presser 63 is preferably comprised of a plurality of deep notches 64 to engage the passing needles in

order to rotate the presser in time with the rotation of the needle cylinder. At predetermined intervals on the periphery, there are provided shallow notches 66 which receive the passing needles and exert sufficient pressure upon them to force the needle beards 31 into the recesses 32.

With this revolving presser, those needles which are contacted by the shallow notches 66 are pressed so that stitches pulled up from the bases of the pressed needles pass over the depressed needle beards. As these stitches are pulled up farther over the depressed beards, they engage the yarn or thread passing thru the heads or hooks in the needles and are finally pulled off. On the other hand, needles which are engaged by the deep slots 64 are not sufficiently pressed so that their beards pass into the recesses 32, and thus old stitches raised from their position adjacent the base of the needles pass into the heads at the upper end of the needles without being cast off. This action is illustrated by the diagrammatic needles in Fig. 3. The cooperation of the lander bur 62 and the cut presser 63 is such that predetermined ones of the old stitches on certain of the needles are pulled off and pass into the knit material while others of the stitches are simply reinserted into the 85 looped or hooked upper ends of the needles.

Ordinarily, the lander bur is not capable of casting off from the needles stitches which have been released by the action of the cut presser 63. I therefore provide a cast-off bur 67 mounted on a clamp 54 on the inner circle and adapted to discharge from the needles all of the stitches which have been freed by the joint action of the lander bur 62 and the cut presser 63. All of the burs and wheels just described are taken together to provide one of the feed units in accordance with my invention. These feed units are preferably alternated with other feed units of somewhat different characteristics, one of which is disclosed in the right hand portion of Fig. 1.

This subsequent feed unit preferably includes means for inserting a backing thread into the material. A backing bur 68 is expediently mounted on a suitable sinker post 41 provided with a feed regulator 69 which conducts a thread or yarn around the backing bur into the needles. It is customary to provide blocks or projections between the various selected blades of the backing bur 68 so that the backing thread is interlaced between various ones of the needles in any pattern or manner desired. This feature is well known in the art and is not minutely illustrated.

In order to facilitate the operation of the backing bur 68 there is preferably provided a cloth cam 48 which depresses the cloth just in advance of the backing bur and forces the stitches from the upper portions of the 130

needles down to their bases. The backing thread is thus interlaced among the needles and lies above the old stitches situate at the needle bases. Following the backing bur 68

5 I preferably provide a clearing bur 70 which is similar to the clearing bur 58 and likewise is mounted on a suitable sinker stand 41. The clearing bur insures that the backing yarn introduced over the bur 68 lies adjacent the 10 bases of the needles just above the old stitches situate thereon.

Trailing the clearing bur 70 I provide another sinker bur 71 mounted on a suitable stand and adapted to sink a thread, running 15 thru an eyelet 72, into and beneath the beards of the needles passing by. This thread engages the succeeding heads of all of the passing needles and is adapted to form loops when the old stitches are raised by a second 20 lander bur 73 supported by a clamp 54 on the inner ring 51. The lander bur 73 works in cooperation with a presser 74 situated on the outside of the needle cylinder and suitably supported by a sinker stand 41. The 25 presser 74 is stationary and is substantially a cam of such contour and height that it depresses the beards 31 of all of the needles passing it into their cooperating recesses 32

In this fashion all of the material which 30 passes the presser 74 and the lander bur 73 is manipulated so that the old stitches lying adjacent the bases of the needles are lifted over the depressed beards of the needles and interlooped with the thread just introduced 35 by the sinker bur 71. The work of the lander bur 73 is facilitated and extended by a second cast-off bur 76 situated on the inner side of the needle cylinder and mounted by a suitable clamp 54 on the inner ring 51. The bur 76 40 casts off the old stitches from the needles, leaving interengaged with the needle loops the new stitches formed by the thread introduced over the sinker bur 71.

This unit of the feed mechanism is preferably combined with the feed unit previously described to form a group. There are any number of similar groups employed on a given knitting machine depending primarily upon the number of threads to be introduced 45 and the size of the machine. If more than one such group is employed, I preferably alternate the unit with the cut presser wheel first described, with the unit last described which usually employs a presser of the cam type.

It therefore occurs that in one feed unit, a backing thread is introduced into the material and all of the old stitches are cast off, while in the other unit of the feed group, an 50 additional thread is introduced, but only predetermined ones of the stitches on certain of the needles are cast off, the others being retained until the next group of feed units is encountered. This operation continues for each feed group employed.

I have found that the machine described produces a novel fabric or material which is substantially non-extensible or stretchable. The machine employs a large number of standard parts and is easily arranged to produce standard material. Also, it can be quickly rearranged to provide almost endless patterns and types of special materials.

It is to be understood that I do not limit myself to the form of knitting machine shown 70 and described herein, as the invention, as set forth in the following claims may be embodied in a plurality of forms.

I claim:

1. A knitting machine of the cylinder 80 spring needle type comprising a feed including in succession a backing bur, a sinker bur, a presser, a lander bur, and a cast-off bur; alternated with a feed including in succession a sinker bur, a lander bur, a cut presser, and 85 a cast-off bur.

2. A knitting machine of the cylinder spring needle type comprising a feed including in succession a backing bur, a clearing bur, a sinker bur, a presser, a lander bur, and 90 a cast-off bur; alternated with a feed including in succession a clearing bur, a sinker bur, a lander bur, a cut presser, and a cast-off bur.

3. A knitting machine of the cylinder 95 spring needle type comprising a feed including in succession a blocked backing bur, a clearing bur, a sinker bur, a presser, a lander bur, and a cast-off bur; alternated with a feed including in succession a clearing bur, a sinker bur, a lander bur, a cut presser, and a cast- 100 off bur.

4. A knitting machine of the cylinder spring needle type comprising means for holding old stitches adjacent the bases of the needles, means for introducing a backing 105 thread onto the bases of said needles, means for introducing a thread under the beards of said needles, means for lifting said old stitches off of said needles thereby lifting off said backing thread and leaving new stitches 110 on said needles, means for disposing said new stitches adjacent the bases of the needles, means for introducing another thread under the beards of said needles, and means for lifting predetermined ones of said new stitches 115 off of certain of said needles.

5. A knitting machine of the cylinder spring needle type comprising means for introducing backing thread onto said needles, means for introducing stitch thread onto 120 said needles, means for pulling stitches together with said backing thread off of said needles, means for introducing an additional thread onto said needles, and means for pulling only predetermined ones of the stitches formed by said additional thread off of said needles.

6. In combination with a circular series of 125 spring needles of a knitting machine, a clearing bur for carrying fabric from the tops to 130

the bases of the needles, a sinker bur for laying a yarn or thread into the heads of the needles, a cut presser having slots of different depths in its edge for engaging and depressing only predetermined needles, a lander bur to raise stitches formed on depressed needles upwardly over the needle beards forming a loop and stitches on needles engaging deeper slots upwardly into the hooked end of the needles, and a cast off bur; in alternate arrangement with a backing bur for laying a backing thread or yarn above old stitches, a clearing bur, a sinker bur for sinking a thread beneath the beards of the needles, a lander bur, a plain presser, and a cast off bur for lifting all stitches over the needles to form a loop with the thread or yarn from the last mentioned sinker bur.

7. In a feed combination for a knitting machine having a circular series of spring needles, a first feed group including a clearing bur, a sinker bur feeding a thread or yarn upwardly into the needles, a lander bur raising old stitches upwardly along the shanks and above the beards of the needles, a cut presser cooperating with the lander bur and engaging and depressing selectively only certain of the needles whereby some of the stitches raised by the lander bur pass over and others pass under the needle beards, the stitches passing upwardly and over the needle beards forming loops, and a cast off bur casting off stitches freed by the joint action of the cut presser and lander bur; and a second feed group including a cloth cam, a backing bur feeding a backing thread or yarn in interlaced relation with the needles above old stitches, a clearing bur, a sinker bur sinking a thread or yarn beneath the beards of all needles; a lander bur raising all stitches, a plain presser cooperating with the lander bur, and a cast off bur casting off the stitches from all needles.

8. A knitting machine of the cylinder type comprising a frame, a series of spring needles rotatably mounted with respect to the frame, a first feed mounted on the frame including a backing bur, a sinker bur, a lander bur, a plain presser, and a cast off bur to replace old stitches with new stitches on all passing needles; and a second feed mounted on the frame including a sinker bur, a lander bur, a cut presser cooperating with the lander bur, and a cast off bur to replace old stitches with new stitches on only predetermined needles passing the second feed.

In testimony whereof, I have hereunto set my hand.

SIMON D. COHEN.
